UNITED STATES PATENT OFFICE

2,670,541

RULER

Hans Priess, Nienburg an der Weser, Germany

Application May 16, 1951, Serial No. 226,577

1 Claim. (Cl. 33—109)

1

This invention relates to rulers adapted in use to roll over the drawing sheet, the rolling means comprising two rollers mounted on a common spindle.

The object of the invention is to provide an accurate parallel ruler of the above kind i. e. a ruler parallel movement of which is not affected by obstruction such as eraser particles or dust which may be present on the drawing sheet.

With the foregoing object in view in a ruler of the kind referred to made in accordance with the invention the rollers and spindle are disposed adjacent the drawing edge of the ruler so that the lower edge of said ruler rests on the drawing sheet, and tooth-like projections are provided on the lower surface of said bottom edge, said projections extending perpendicularly to said spindle.

The result of this arrangement is that the movement of the ruler is directed in such a way as to maintain parallel movement in the event that a force acts on either one of the rollers tending to oppose this parallel movement; which force may be produced, for example, by eraser dust, in the path of one or both of the rollers.

In order further to eliminate as much as possible any action tending to oppose the parallel movement, the peripheral surfaces of the rollers are in addition fluted or grooved in a known way. As a result, any particles detached from a rubber eraser can be rendered harmless since they pass into the flutes or grooves of the rollers and in consequence are not rolled over.

The invention is illustrated in the accompanying drawing, in which:

Figure 1 is a plan view of a roller ruler made according to the invention;

Figure 2 is a cross section taken on line II—II, Figure 1;

Figure 3 is a detail plan view of a preferred embodiment of the ruler;

Figure 4 is a view in cross section taken on line IV—IV, Figure 3;

Figure 5 is an underneath view of the ruler, and

Figures 6 and 7 are detail views.

The ruler shown in the drawings is provided with two rollers 7 mounted adjacent to the ends of the ruler on a common spindle 8. The spindle 8 is located in a groove 9. As shown in Figure 1 the spindle 8 is mounted in position with the rollers 7 by screws 10, which have conical ends 12 engaging in corresponding conical recesses in the rollers.

2

The spindle 8 and rollers 7 are not located along the centre of the ruler, but on one side of the longitudinal centre line and adjacent to the drawing edge 11.

As shown in Figures 3 and 4 the ruler is provided centrally on its top surface with a trough-shaped depression 14, in which the user's fingers can be laid when the ruler is in use. The depression 14 is so arranged that its longitudinal centre line 15 is disposed below and spaced somewhat from the spindle 8, the centre line 15 being therefore relatively widely spaced from the lower edge 16 of the ruler.

As shown in Figure 5 the bottom underneath edge 16, 17 of the ruler, which rests on the drawing sheet is formed with a series of parallel projections spaced from one another and having sufficient length to extend perpendicularly to the roller spindle, to permit unobstructed movement of the ruler over any eraser dust that may be present on the drawing sheet. If the surface 16, 17 were continuous, undesired alterations in the position of the ruler could occur during movement of the ruler by reason of the eraser dust.

As shown in Figure 6 the rollers 7 also have a discontinuous peripheral surface produced by flutes or grooves in this surface, which prevent obstruction to the movement of the ruler by any eraser dust which may be present on the drawing sheet.

Figure 6 also shows the mounting of the rollers 7 and of the spindle 8. The point 18 of the rollers 7 bears in a boring in a metal angle member 19, which is connected with the ruler by the headed screw 20. The screw 20 passes through a slot 21 in the ruler, so that the angle member 19 can be adjusted in the longitudinal direction of the ruler.

Figure 7 shows a modified form of roller having a U-shaped periphery. The recessed part 1a of the roller carries uniformly distributed sighting marks 13. These sighting marks co-operate with a fixed sighting mark on the ruler to indicate the amount of displacement of the ruler. The spacing of the sighting marks 13 on the two rollers can be different, for example to denote displacements of the ruler by one millimeter and by five millimeters.

The material of the ruler is only of secondary importance for the invention. The ruler can be made of wood, metal, plastic or the like.

What I claim is:

A ruler fitted with rolling means comprising 55 two rollers and a spindle on which said rolling

means are commonly mounted, said rollers being formed with peripheral grooves and said ruler having a flat top surface formed midway of its length with a finger depression having a length corresponding substantially to the width of a user's fingers, said rollers and said spindle being disposed adjacent the drawing edge of the ruler so that the lower edge of said ruler rests on the drawing sheet, and further comprising a series of parallel projections from the lower surface of said bottom edge, said projections being spaced from one another and having sufficient length to extend perpendicularly to said spindle and acting to maintain parallel movement of the ruler.

10

HANS PRIESS.
